CHARLES F. MILLER, OF MOORES, PENNSYLVANIA, ASSIGNOR TO WESTINGHOUSE ELECTRIC & MANUFACTURING COMPANY, A CORPORATION OF PENNSYLVANIA

UNDERFEED STOKER CONSTRUCTION

Application filed February 21, 1930. Serial No. 430,325.

My invention relates to stokers and more particularly to that type which comprises parallel and alternately-disposed retorts and rows of tuyères, and it has for a broad object 5 to improve the construction and arrangement of this type of apparatus.

In certain stokers of this type, it has been the practice to support each side wall of each retort from a separate beam structure and to 10 support the rows of tuyères directly from the upper edges of the side walls of the retorts. According to a preferred embodiment of the 15 present invention, instead of providing a separate supporting beam for each retort side wall, I provide a beam structure for supporting each two adjacent side walls of adjacent retorts. Also, I provide structure for supporting the tuyères independently of the retort side walls, so that the side walls may be re- 20 placed without disturbing the tuyères. More particularly, therefore, a further object of my invention is to provide a multiple retort stoker wherein the retorts are supported in this way and wherein the tuyères are sup- 25 ported independently of the retort side walls.

A further object of my invention is to provide, in a multiple retort underfeed stoker, a structural frame work for supporting cast iron, fuel-contacting parts and including I- 30 beams disposed beneath the tuyère rows and having elements secures thereto for supporting adjacent retort side walls and for sup- 35 porting the tuyères independently of the retort side walls.

These and other objects are effected by my invention, as will be apparent from the following description and claims, taken in connection with the accompanying drawings, forming a part of this application, in which:

40 Fig. 1 is a longitudinal sectional view illustrating a multiple retort underfeed stoker constructed in accordance with my invention, the view being taken on the line I—I of Fig. 3;

45 Fig. 2 is a fragmentary plan view of the

apparatus shown in Fig. 1, certain parts being removed to illustrate the details of construction;

Fig. 3 is an enlarged fragmentary sectional view taken on the line III—III of Fig. 1; 50 and,

Fig. 4 is a fragmentary sectional view taken on the line IV—IV of Fig. 1, and illustrating the construction at the lower end of the stoker. 55

Referring now in detail to the construction illustrated, it will be observed that I have shown a downwardly-inclined underfeed stoker comprising parallel and alternately-arranged retorts 10 and rows of tuyères 11. The retorts comprise upright side walls 12 formed of sections 13 secured in end-to-end relation, and a bottom wall 14 disposed between the side walls and supported by brackets 15 carried by flanges 16 extending laterally from the lower edges of the retort side walls. The adjacent ends of the sections 13 are detachably secured together by clamping plates 17 and bolts 18 passing through the plates and the sections. The tuyères 11 are disposed in overlapping relation and form a cover for the space between the adjacent side walls of adjacent retorts. 70

The retorts and the tuyères form the fuel-supporting surfaces for the stoker and are supported by frame structure disposed therebeneath. The frame structure includes parallel I-beams 20 carried at their upper and lower ends by castings 21 and 22, respectively, which latter are in turn supported by upper and lower transversely-extending I-beams 23 and 24, respectively. The casting 21 is bolted to the beam 23. The casting 22, however, is slidable on the beam 24 to permit longitudinal expansion of the stoker. The arrangement of the I-beams 20 is such that there is one beam disposed between the two adjacent side walls of adjacent retorts and directly beneath the tuyères closing the space between such side walls. 85 90

One or more frame-like castings 25 are supported by the upper flange of each of the I-beams and comprise a bottom plate 26 bolted to such flange of the I-beam, a pair of side pieces 27 disposed parallel and adjacent to the retort side walls and cross members 28 connecting the side pieces with the bottom plate 26.

The retort side walls 12 are secured at their upper edge to the adjacent side pieces 27 by means of bolts 30 extending through the side walls and through boss-like extensions 31, formed on the walls and through the side piece. The lower portions of the side walls 12 are provided with additional extensions 32. The extensions 32 engage at their outer ends the lower flange of the I-beam and thereby provide a means for holding the lower portion of the retort side walls in proper position.

The tuyères 11 are supported independently of the retort side walls. The tuyères rest upon the upper surface of the side pieces 27 and are provided with lugs 33 which cooperate with lugs 34 formed on the outer sides of the side pieces 27, to hold the tuyères in proper spaced relation. As an additional means of holding the tuyères in proper position, they are each provided with a downwardly-extending projection 35 and a slot 36, the projection 35 of one tuyère fitting within the slot 36 in the tuyère immediately below.

From the foregoing, it will be seen that I have provided a supporting frame construction for a multiple retort underfeed stoker wherein the tuyères are carried independently of the retort side walls, this mode of supporting being advantageous from the points of view of relative expansion and contraction of the cast iron elements and of making it possible to replace the retort side walls without disturbing the tuyères. Furthermore, as the principal supporting elements are I-beams, my construction has the advantage of using a very desirable type of beam structure on account of strength, straightness, and independence of design from the retort side walls. Also, the brackets for supporting the retort side walls serve to prevent overheating of the beam structures and they provide a convenient means for securing alignment of the sections of the retort side walls. Not only may beams of the most desirable design be used when located in this way, but they serve the double purpose of supporting the retort side walls and the tuyères.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

1. In an underfeed stoker having alternately-arranged retorts and tuyère rows, a supporting construction for the stoker including a beam arranged below each tuyère row and connected to adjoining side walls of adjacent retorts, and means connected to each beam for supporting the tuyères of the row thereabove independently of the retort side walls.

2. In stoker apparatus, the combination of a combustion grate comprising a plurality of spaced parallel retorts and a row of tuyères closing the space between the retorts; each of the retorts comprising side walls formed of sections and bottom-forming members disposed between the side walls; a supporting frame for the combustion grate comprising a plurality of spaced beam structures disposed parallel to and alternate with respect to the retorts; means for detachably supporting the two adjacent side walls of adjacent retorts to their respective beam structure; and means other than the retort walls for detachably supporting the tuyères from the beam structure.

3. In stoker apparatus, the combination of a plurality of spaced parallel retorts, each of which comprises side walls formed of sections and bottom-forming members disposed between the side walls; a row of tuyères closing the space between adjacent retorts; a plurality of parallel beam structures for supporting the retorts, there being one beam structure for each two adjacent side walls of adjacent retorts; means for detachably securing the sections forming the two adjacent side walls of adjacent retorts to their respective beam structure; and means other than the retort walls for detachably supporting the tuyères from the adjacent beam structure.

4. In stoker apparatus, the combination of a plurality of spaced parallel retorts each of which comprises side walls formed of sections and bottom-forming members disposed between the side walls; a row of tuyères closing the space between adjacent retorts; a plurality of parallel beam structures for supporting the retorts, there being one beam structure for each two adjacent side walls of adjacent retorts; means for detachably securing the sections forming the two adjacent side walls of adjacent retorts to their respective beam structure and including means other than the retort side walls for supporting the tuyères from such beam structure.

5. In stoker apparatus, the combination of a plurality of spaced parallel retorts each of which comprises side walls formed of sections and bottom-forming members disposed between the side walls; a row of tuyères closing the space between adjacent retorts; a plurality of parallel beam structures for supporting the retorts, there being one beam structure for each two adjacent side walls of

adjacent retorts; a frame-like structure secured to each beam structure and including a side piece disposed adjacent each retort side wall; means for detachably securing the retort side walls to the adjacent side pieces; and means for detachably supporting the tuyères from the adjacent side pieces.

5 In testimony whereof, I have hereunto subscribed my name this 17th day of February, 10 1930.

CHARLES F. MILLER.
